UNITED STATES PATENT OFFICE.

MARTIN P. ROLLINS, OF CHERRYDALE, VIRGINIA.

SUPPORT FOR MULTIGRAPH-SEGMENTS.

1,338,964.

Specification of Letters Patent.

Patented May 4, 1920.

Application filed August 5, 1919. Serial No. 315,507.

To all whom it may concern:

Be it known that I, MARTIN P. ROLLINS, a citizen of the United States, residing at Cherrydale, in the county of Alexandria and 5 State of Virginia, have invented a new and useful Support for Multigraph-Segments, of which the following is a specification.

This invention is a device for supporting the type holding segments of a multigraph 10 printing machine.

In setting up printing matter for the duplicating machine known as the "multigraph" it is common practice to employ a type setting system in which the type are 15 removed from suitably arranged banks and set up in single lines in what is known as a composition fork. Each line as it is completed is transferred from the composition fork to a channel of the type segment of 20 the multigraph machine. It is customary to place the type segment on a table or other support, and to hold it with one hand while transferring the type thereto with the other hand. Because of the peculiar shape 25 of the segment it cannot be firmly held on a flat surface while transferring the type, and as a consequence the segment frequently slides around on the table, causing delay and annoyance in the composition work.

30 The object of the invention is to overcome the foregoing objection by providing means for so holding the segment while transferring type thereto, that it cannot slip, thereby saving time and labor.

35 The invention will be hereinafter fully set forth and particularly pointed out in the claims.

In the accompanying drawing:—

Figure 1, is a top plan view illustrating 40 a holding device constructed in accordance with the invention. Fig. 2 is a side elevation thereof. Fig. 3 is a detail longitudinal sectional view.

Referring to the drawings, 10 designates 45 a base, preferably rectangular in plan view, provided at one end with a cleat 11 and at the other end with a plurality of cleats 12. Located in the space between the cleat 11 and the cleats 12 is an anchor member 13, 50 provided with an inclined front edge 14, terminating in an overhanging shoulder 15, contiguous to the top surface of the base 10. The rear edge 16 of the anchor member is curved as indicated and spaced a relatively

short distance from the cleat 11. The anchor member 13 is relatively narrow and projects upwardly from the top surface of the base 10 at the longitudinal median line. 55

The base 10, the cleats and the anchor member may be made of any suitable material, for instance either wood or metal, but in the drawings the parts are illustrated as made of stamped metal, the cleats being formed integral with the base, the anchor member being secured to the base by means 60 of screws 17. The base is also provided with a bottom plate 18 to which may be attached suitable cushioning material.

In practice, when it is desired to transfer type to a multigraph segment, one edge of 70 the segment is hooked under the overhanging shoulder 15 so as to support the other edge of the segment in a position to receive the top lines of type. As the composition progresses the lower edge of the segment 75 is disengaged from the shoulder 15 and brought against the innermost cleat 12 so as to bring another portion of the segment in a convenient position to receive the type. As the composition progresses the segment 80 is shifted successively into engagement with the other cleats 12 until finally the bottom edge engages the outermost cleat 12 and the top edge engages the cleat 11. During all this time the segment is held from sliding 85 first by engagement with the shoulder 15 and the anchor member, and later by the anchor member and the cleats. In this manner the composition work is greatly facilitated and is accomplished with much less labor 90 than it would be under conditions where the invention is not used.

Having thus explained the nature of the invention and described an operative manner of constructing and using the same, although without attempting to set forth all of the forms of its use or all of the forms in which it may be made, what is claimed 95 is:—

1. A support for multigraph segments 100 comprising a base provided with an anchor member and cleats in spaced relation to said anchor member.
2. A support for multigraph segments 105 comprising a base provided with an anchor member having an overhanging shoulder and cleats in spaced relation to said anchor member.

3. A support for multigraph segments comprising a base provided with a cleat at one end and a plurality of cleats at the other end, and an anchor member in juxtaposition with said cleats.
4. A support for multigraph segments comprising a base provided with a cleat at one end and a plurality of cleats at the other end, and an anchor member attached to said base in juxtaposition with said cleats.
5. A support for multigraph segments comprising a base provided with integral cleats, and an anchor member attached to said base in juxtaposition with said cleats.
- 10 6. A support for multigraph segments comprising a base provided with integral cleats, an anchor member attached to said

base in juxtaposition to said cleats, and a base plate attached to said base.

7. A support for multigraph segments comprising a base provided with integral cleats, and an anchor member attached to said base in juxtaposition with said cleats, and provided with an overhanging shoulder.

8. A support for multigraph segments comprising a base provided with cleats, and a relatively narrow anchor member attached to said base along the longitudinal median line thereof and in juxtaposition with said cleats.

30 In testimony whereof I have hereunto set my hand.

MARTIN P. ROLLINS.
